United States Patent Office

Des. 194,855

Patented Mar. 19, 1963

194,855

BOTTLE CARRIER

William J. Lawrence, Jr., Clifton, and Louis R. Petrone,
East Orange, N.J., assignors to W. R. Grace & Co.,
New York, N.Y., a corporation of Connecticut

Filed Sept. 19, 1962, Ser. No. 71,780

Term of patent 14 years

(Cl. D58—26)

The figure is a perspective view of a bottle carrier showing our new design.

The fragmentary, broken line showing of a bottle in one of the carrying-holes is for illustrative purposes only.

We claim:

The ornamental design for a bottle carrier, as shown and described.
